DESIGN FOR A CHILD'S AEROVELOCIPED

Joseph F. Jones, Cortland, N. Y.

Application December 5, 1944, Serial No. 116,719

Term of patent 14 years

(Cl. D34—15)

To all whom it may concern:

Be it known that I, Joseph F. Jones, a citizen of the United States and a resident of Cortland, in the county of Cortland and the State of New York, have invented a new, original, and ornamental Design for a Child's Aerovelocipede, of which the following is a specification, reference being had to the accompanying drawings forming part thereof, in which:

Fig. 1 is a perspective view of a child's aerovelocipede showing by new design.

Fig. 2 is a top view thereof, and

Fig. 3 is a front end view thereof.

I claim:

The ornamental design for a child's aerovelocipede, as shown.

JOSEPH F. JONES.
